CLAIM

The ornamental design for a tire, as shown and described.

DESCRIPTION

FIG. 1 is an enlarged partial front elevation view of the tire showing my new design;

FIG. 2 is a front perspective view thereof;

FIG. 3 is a front elevation view thereof;

FIG. 4 is a top elevation view thereof;

FIG. 5 is a left side elevation view thereof; and,

FIG. 6 is a right side elevation view thereof.

The dash dot broken line in FIG. 3 is a demarcation of the portion of the tire shown in the enlarged partial front view of FIG. 1 and forms no part of the claimed design.
